CULVERT

Adolph Schroeder, Jr., Yorktown, Tex.

Application October 27, 1934, Serial No. 750,374

4 Claims. (Cl. 72—52)

The present invention relates to new and useful improvements in culverts and has for its primary object to provide a structure of this character comprising a plurality of preformed members 5 adapted to be molded at a factory and then transported to the desired location and assembled.

Another important object of the invention is to provide a culvert of the aforementioned character which comprises novel means for firmly 10 securing the preformed members in assembled position.

Other objects of the invention are to provide a sectional culvert which will be comparatively simple in construction, strong, durable and which 15 may be manufactured and erected at low cost.

All of the foregoing and still further objects and advantages of the invention will become apparent from a study of the following specification, taken in connection with the accompanying 20 drawings wherein like characters of reference designate corresponding parts throughout the several views, and wherein:

Figure 1 is a view in side elevation of a culvert constructed in accordance with the present invention.

Figure 2 is a top plan view thereof.

Figure 3 is a view in vertical transverse section, taken substantially on the line 3—3 of Figure 1.

Figure 4 is a view in vertical longitudinal section through one end portion of the culvert, taken substantially on the line 4—4 of Figure 2 with parts broken away in section.

Figure 5 is a detail view in perspective of one of the side slabs.

Figure 6 is a detail view in perspective of one of the L irons.

Figure 7 is a detail view in perspective of one of the baffles.

Referring now to the drawings in detail, it will 40 be seen that the embodiment of the invention which has been illustrated comprises parallel series of footing sections 1 which are assembled end to end. As illustrated to advantage in Figure 3 of the drawings, the footings 1 are tapered 45 and include anticalinal for substantially V-shaped tops 2. The bottoms of the footings 1 have formed therein longitudinal grooves 3 for the reception of tie rods 4, the end portions of which are threaded to receive nuts 5. Substantially 50 L-shaped irons 6 are mounted on the tie rods 4 between the nuts 5 and the end footings 1, said L irons extending beneath the end footings and also rising thereabove. This is shown to advantage in Figure 4 of the drawings.

55 Mounted vertically on the footings 1 are side

slabs 7 the lower ends of which are substantially V-shaped, as at 8, to conform to the tops 2 of said footings 1. The footings 1 extend beyond the side slabs 7 and have mounted thereon end wings 9 the upper ends of which are inclined. The lower ends of the end wings 9 are substantially V-shaped to receive the tops 2 of the footings 1. It will be noted that the L irons 6 engage and retain the outermost wing members 9.

Mounted on the upper ends of the side slabs 10 10 are transversely extending top slabs 10. As shown to advantage in Figure 1 of the drawings, the joints of the side slabs 7 are staggered relative to the joints of the footings 1 and the top slabs 10. The outermost top slabs 10 are formed 15 to provide upstanding curbs 11. The upper ends of the side slabs 7 have formed therein longitudinally extending grooves 12 which receive tie rods 13 having threaded end portions extending through the adjacent upper portions of the 20 innermost wing members 9 (see Figure 4). Retain nuts 14 are threaded on the tie rods 13, washers 15 being interposed between said nuts 14 and the wing members 9 through which said tie rods 13 pass. The innermost wing members 25 9 extend above the side slabs 7 and are engaged with the outermost top slabs 10, as also shown to advantage in Figure 4.

Mounted in the lower portion of the ends of the culvert proper are baffles 16. The baffles 16 are 30 provided with inclined ends 17 which conform to the inner sides of the footings 1 with which said baffles are engaged.

It will thus be seen that the lower tie rods 4 firmly clamp the footing sections 1 comprising 35 each series together and, through the medium of the L irons 6 said lower tie rods 4 clamp the wing members 9 and the side slabs 7 together. The upper tie rods 13 clamp the innermost wing members 9, in which said tie rods 13 are engaged, and 40 the upper ends of the side slabs 7 together and also the top slabs 10 by reason of the fact that said innermost wing members 9 are engaged with the outermost top slabs. The baffles 16 prevent 45 the soil which constitutes the floor of the culvert from being washed away by the water flowing through said culvert. The construction and arrangement is such that a culvert of any desired dimensions may be rapidly constructed with a minimum of labor.

50 It is believed that the many advantages of a culvert constructed in accordance with the present invention will be readily understood and although a preferred embodiment of the invention is as illustrated and described, it is to be under- 55

stood that changes in the details of construction and in the combination and arrangement of parts may be resorted to which will fall within the scope of the invention as claimed.

5 What is claimed is:

1. A culvert of the class described comprising parallel series of footings, side slabs rising vertically from the footings, top slabs mounted transversely on the side slabs, the footings extending beyond the side slabs, wing slabs mounted on the footings beyond the side slabs, and common means for clamping the footings, side slabs and the wing slabs together in assembled relation.

10 2. A culvert of the class described comprising parallel series of footing sections, side slabs mounted vertically on the footing sections, said footing sections extending beyond the side slabs, means for securing the footing sections together in end to end relation, top slabs mounted transversely on the side slabs, wing slabs mounted on the footing sections beyond the side slabs and engaged with the outermost side slabs and with the outermost top slabs, and common means for clamping the wing slabs, the side slabs and the top slabs together in assembled relation.

15 3. A culvert of the class described comprising footing sections, side slabs rising from the footing sections, said footing sections extending beyond the side slabs, top slabs mounted on the

side slabs, wing slabs mounted on the projecting footing sections and engaged with the outermost side slabs and the outermost top slabs, said side slabs having longitudinal grooves in their upper ends, tie rods mounted in the grooves and anchored in certain of the wing slabs for clamping said certain wing slabs, the side slabs and the top slabs together in assembled relation, the footing sections having longitudinal grooves in their bottoms, tie rods mounted in the last named 10 grooves, and members mounted on the end portions of said tie rods and engaged with the other wing slabs for clamping the wing slabs and the footing sections together in assembled relation.

4. A culvert of the class described comprising 15 tapered footing sections including substantially V-shaped tops, side slabs mounted vertically on the footing sections and including substantially V-shaped lower ends conforming to the tops of the footing sections, said footing sections extending beyond the side slabs, wing slabs mounted on the extending footing sections, baffles mounted transversely adjacent the wing slabs, said baffles having inclined ends engaged with the adjacent 20 footing sections, a tie rod securing the footing 25 sections together, top slabs mounted on the side slabs, and tie rods securing certain of the wing slabs, the side slabs, and the top slabs together.
